TRANSFER LABELING MACHINE

Russell A. Phipps, Woodville, Mass., assignor to Dennison Manufacturing Company, Framingham, Mass., a corporation of Massachusetts

Filed Sept. 8, 1960, Ser. No. 54,603

9 Claims. (Cl. 156—541)

This invention relates to a transfer labeling machine of the general type involved in United States Patent of Gottscho et al., No. 2,874,499. In machines of that type a rotatable die segment presses a label against the article to be labeled, and under the influence of heat and pressure the label adheres to the surface of the article. While hot, the label has little adhesion for the label-carrying strip which has presented it to the die. Thus it is possible to detach the label-carrying strip from the label and leave the label adhering to the article.

In general the invention aims to improve the certainty with which the label-carrying strip is detached or caused to "break away" from each successive label. If there is any delay in break away so that there is any slight cooling of the film between the ink of the label and the paper of the label-carrying strip, this film will reharden and some of the ink which should form part of the applied label will instead be carried off by the label strip. The invention involves control of tension and direction of the label-carrying strip with a view to making the break away as reliable as possible.

In the accompanying drawings,

FIG. 1 is a partly diagrammatic front elevation of the machine;

FIG. 2 is a partly diagrammatic rear elevation;

FIG. 3 is a diagrammatic view taken from the same point of view as FIG. 1 but showing principally structure which is behind the front plate, mainly a train of driving connections which lie between the front and rear plates;

FIG. 4 is a generally vertical sectional view on the line 4—4 of FIG. 1;

FIG. 4a is similar to FIG. 4, being taken on that portion 4a—4a of the line 4—4 so indicated in FIG. 1;

FIG. 5 is a sectional view taken on line 5—5 of FIG. 1;

FIG. 6 is a diagrammatic view in which parts are omitted and broken away, taken generally on the line 6—6 of FIG. 1;

FIG. 7 is a diagrammatic view from the front of the machine showing the position of the label-carrier strip during inaction of the die; and

FIG. 8 is a view similar to FIG. 7 showing the strip leaving the active surface of the die.

The drawings show mainly the operative head of the machine, it being understood that this head can be applied to various base structures which will support the material or articles being labeled.

For separate articles, conveyor structure appropriate to the articles will be selected and the head applied thereto. In the drawings such conveying structure is diagrammatically shown at 20, comprising an element moving in a plane and, if desired, having suitable cleats 21 for engaging articles 22 which may be containers having flat surfaces.

For applying labels to webs there may be substituted suitable web conveying mechanism and a back-up roll for holding the web against the die, as in said Patent No. 2,874,499, such a roll being shown in phantom line in FIG. 1.

The main frame of the head comprises a front plate 25, FIG. 1, and a rear plate 26, FIG. 2, connected by suitable cross connections including a bottom web 27

2

and sleeve 28. Various shafts also extend between and are mounted in bearings in these plates as will be apparent.

A main drive shaft 30 extends through bushings in both plates. The main shaft is suitably driven and is supported in exterior supports and itself constitutes the support for one end of the head. The head can be shifted laterally toward or away from the observer in either FIG. 1 or FIG. 2, along the main drive shaft 30, to position the device to act on the desired part of an article or to accommodate articles of different sizes. The head may also be swung counterclockwise in FIG. 1 and clockwise in FIG. 2 about the shaft 30 to give access to parts which are otherwise inaccessible.

The end of the head opposite to the main drive shaft 30 is supported by an adjusting pin 32 whose lower end rests on some stationary abutment 33 upon the base structure.

The pin 32 extends through and is screw-threaded into a plug 34 within the tube 28. By rotational adjustment of the pin, the end of the head can be raised and lowered with a fine degree of accuracy, to adjust the pressure of application of the label.

The driving connections are mostly shown in FIG. 3, aided by reference to FIGS. 1 and 2. A gear 40 splined on the continually rotating main drive shaft 30, drives the continually rotating gear 41 of a one-revolution clutch 42 of a well-known construction. Gear 41 has fast thereon a sprocket 43 which turns continuously as a part of driving connections to label-strip rewinding mechanism explained below. The clutch trip lever 45 is withdrawn from the clutch trip cam 46 by an electrical impulse energizing a solenoid 48. The solenoid 48 may be controlled by switching means under the control of any suitable timing means, and for example, as described by said patent, the timing of the switching means may be accomplished by a machine which uses the labeled web in the case of operating the labeling machine to label a web.

One impulse applied to the solenoid accordingly permits one revolution of the output portion of the clutch 42 which carries a gear 50. Through an idler gear 51 this one revolution imparts one revolution to a gear 52 fast on a shaft 53 on which is fast a cylinder or wheel 54, FIG. 1, carrying the heated segmental die or iron 55.

Returning to FIG. 3, gear 52 through idler gear 58 drives a gear 59 which is loose upon sprocket shaft 60. Gear 59 serves to drive the shaft 60 frictionally through friction members 61, FIG. 4. The shaft 60 carries at the front side of the machine, FIG. 1, a sprocket wheel or drum 63, and at the rear side of the machine, FIG. 2, a ratchet wheel 65.

A cam 67 (FIG. 2) on the rear of the die wheel shaft 53 operates through a follower roll 68 and arm 69 (pivoted at 70) to release a pawl 71 from the ratchet wheel at the start of each revolution of the die wheel and to permit re-engagement of the pawl and ratchet under the influence of a spring 73 at the end of a fraction of a revolution of the sprocket wheel.

As indicated in FIG. 1, the label strip S is guided to the sprocket wheel 63 by idler rolls 80 and 82 and a plurality of tensioning members 81 and is guided away from the sprocket wheel and toward the heated die wheel 54 by idler rolls 83 and 84. By operation of the driving connections above described, for each revolution of the heated die wheel, corresponding to the application of one label, the sprocket wheel 63 delivers to the die wheel a definite length of label strip.

The label strip is supplied from a spool 85, FIG. 1. One flange of this spool carries fast thereon a brake drum 87, FIG. 4. A brake shoe 89, FIG. 1, carried by a block 90 is adapted to bear against the drum. A bell crank 91,

pivoted at 92, is pivoted to the block 90 and a spring 95 urges the bell crank to apply the brake. Bell crank 91 carries a guide roll 97 which receives the label strip from an idler roll 98 over which the strip initially runs in coming off the spool, and roll 97 in turn delivers the label strip to the idler roll 80.

Rotation of the sprocket wheel 63, tends to cause the label strip to draw the roll 97 and depending arm of the bell crank 91 toward the right, thus tending to release the brake. At the same time this movement of the bell crank supplies label strip for travel toward the sprocket wheel in advance of corresponding rotation of the spool 85. As a consequence, the label strip is not called upon to impart a quick acceleration to the spool, and undue strain on the label strip is thus avoided. The brake 89 controlled by the tension in the label strip, prevents the spool from overrunning. In fast operation, a balanced condition is obtained in which the unwinding from the spool is at a practically constant rate just sufficient to supply in a substantially continuous manner the quantity of label strip called for by the successive intermittent movements of the sprocket wheel.

The re-winding spool 105 is driven by connections which include the previously mentioned constantly rotating sprocket wheel 43 of FIG. 3, a chain 107, sprocket wheel 108, jack shaft 109 which reappears in FIG. 1, sprocket wheel 110, FIG. 1, chain 111 and sprocket wheel 112.

Referring to FIG. 5, the constantly rotating sprocket wheel 112 is freely rotatable relative to the shaft 114 of the rewinder spool and carries fast thereon a pressure disc 115 adapted to bear against a ring 116 of friction material which is fast on the hub 117 of the spool. The extent to which the spool is driven depends upon the pressure of disc 115 against ring 116. This pressure is increased as slack increases in the winding strip and reduced as slack decreases, by means of suitable connections such as the following.

A stationary sleeve 120 fast on the frame plate 25 and surrounding the shaft 114 is screw-threaded on the right hand part of its cylindrical exterior surface. A ring 121 has threaded engagement with the sleeve. Ring 121 has a crank 123 extending therefrom. When the crank is moved toward the observer in FIG. 5 ring 121 is displaced toward the right and acts through the casing 125 of a thrust bearing 126 to apply force to a collar 127 which is adjustably held on the rewinder spool shaft 114 by a locking nut 128. This action tends to force the shaft to the right, increasing the pressure between the friction material 116 and the pressure ring 115 and causing the spool to be driven.

When the crank 123 is progressively moved away from the observer in FIG. 5, pressure of the ring 121 upon the thrust bearing casing 125 is progressively relaxed, pressure of the friction material 116 upon the disc 115 is correspondingly relaxed, more slippage occurs and the winding up is reduced.

Crank 123 is controlled by the condition of tension or slack in the winding label strip by suitable means such as the following. The label strip S from which the labels have been transferred is led up in FIG. 1, over a dancing roll 130, and thence down onto the winding body of label strip on the rewinding spool 105. Dancing roll 130 is carried by a bell crank 132 best seen from the rear of the machine in FIG. 2, and this bell crank 132 operates through a link 134 to shift the crank 123.

Bell crank 132 is rotatably mounted on a stationary sleeve 136, FIG. 4a, on an extension of the shaft 137 of the winding spool.

A coil spring 138, interposed between the bell crank 132 and sleeve 136, urges the crank toward the observer in FIG. 4a, tending to lift the dancing roll 130, FIG. 1, tending to operate the rewinding spool, thereby causing a basic tension to be applied to the used label strip in its indirect course toward the winding spool 105.

The previously described friction drive for the winding spool, under control of the dancing roll 130, insures that the label strip is wound up at an average rate such as to accommodate the intermittently fed label strip.

In usual operation, the rotation of the die wheel 54 and the rotation of the feed sprocket 63 are both intermittent. As indicated above, rotation of the die wheel is initiated and stopped by the one revolution clutch 42. Rotation of the die wheel shaft 53 operates through the cam 67, FIG. 2, to disengage the pawl 71 from the ratchet wheel 65 and permit the feed sprocket to be driven. The timing here is in general such that the leading edge of a label on the label strip will coincide with the leading edge of the die segment as the latter reaches the article or web to be labelled.

Exact longitudinal registration of the label strip relative to the die segment is secured by rotational shift of certain of the strip guiding members around the axis of the sprocket wheel. As shown, the guide wheel 80, tensioning members 81 and the guide rolls 82 and 83 are carried by a plate 140 which is rotatable around the axis of the sprocket wheel and relative to an interior stationary ring 140a, FIG. 4. An adjusting screw 142 is threaded into a block 143 (FIGS. 1 and 4) which is rotatable in the plate 140. As indicated in FIG. 1 the right end of screw 142 is rotatably mounted in a block 144 rotatably carried by plate 23. Turning the screw thus turns the plate 140 and those strip guiding members carried thereby. Shifting the guiding members in this way varies the length of path from the sprocket teeth to the line of contact of strip and die segment, without, however, varying the extent of wrap of the strip around the sprocket. A relatively large shift of the guiding members 80, 81, 82 and 83 can be made without interfering with the other parts and without affecting the relation of the strip to the tensioning members 81. The longitudinal registration adjustment can thus be used for both large adjustments incident to changes from labels of one length to labels of a different length, and also for fine adjustment for exactness of registration of a given size of label.

For exact lateral registration of the labels relative to the die wheel and article or web, provision is made for a micrometer adjustment of the sprocket wheel laterally of the strip path.

A rotatable spindle 150 can be rotated manually by its knob 151 to rotate a threaded shaft 152, FIG. 6, through bevel gears 153 and 154. Shaft 152 is threaded into a slideable block 156 which is slotted to receive a flange 158, fast on the sprocket wheel. The sprocket wheel has a splined connection 159 with its shaft 60, and so can be shifted laterally by operating the spindle 150.

The first or upper right hand tension member 81 differs from the other tension members 81 by including a central rod 81a which is fixed to the rotatably adjustable plate 140 and a tube 81b slideable on this rod 81a. Fast to the rear and of this tube 81b is an arcuate rear side guide 160 for the label strip, slotted to receive the flange 158 of the sprocket wheel (FIG. 4) so that lateral adjustment of the sprocket wheel correspondingly adjusts the rear side guide.

An arcuate shaped front side guide 164 is adjustably secured to the tube 81b so as to accommodate strips of various size.

A shaft 100 is oscillated clockwise in FIG. 2 through a crank 100a and link 100b from lever 69 as the cam 67 causes the pawl 71 to disengage the ratchet wheel 65. As shown in FIG. 1 shaft 100 carries a bell crank 101 having a short arm 101a carrying a guide roll 170 and a long arm 101b carrying a guide roll 171. The shaft 100 carries a further freely rotatable guide roll 172. The label strip is guided around rolls 170, 172 and 171 in its course from the guide roll 84 to dancing roll 130, FIGS. 1 and 7 show the strip path when the segmental die 55 is inactive. In this position the co-operating guide rolls 84 and 170 define a straight horizontal course which is substantially tangent to the path through which the die surface will move. This

positioning of the strip will keep the stationary strip out of contact with any of the structure of the hot die wheel 53. In this inactive condition of the strip the take up mechanism which includes dancing roll 130 will be applying the intended basic tension of the strip.

While the die 55 is in the act of transferring the label to the article or web as in FIG. 8, the bell crank 101 will occupy the shifted position shown in that figure, in which the strip is guided away from the surface of the article or web in an upwardly inclined path. This upwardly inclined path to the left of the vertical center line of die wheel 54 in FIG. 8 represents an approach toward the die axis of part of the horizontal run of strip shown in FIG. 7 and a corresponding withdrawal of the label-carrier strip away from the path of the surface receiving the label. In the case of a flat surfaced article this introduces a divergence between the path of the strip and the path of the surface, and in the case of a web, passing over a back-up roll, this increases the divergence of the respective courses of strip and web. In either case, the change in path of guidance of the strip assists in insuring quick and reliable break away of the strip from the label.

The starting up of the feed of the label strip and the shifting of the course of the label strip are not allowed to introduce any momentary lack of tension which would work against reliable break-away of the strip.

The dancing roll 130 affords a means for taking up slack. However, it is desirable to anticipate the action of the dancing roll as the label strip begins to feed and is shifted to its new position. This is accomplished as follows. The strip, as indicated in FIGS. 7 and 8, extends directly from guide roll 171 to the dancing roll 130. Shift of the guide roll 171 from its position of FIG. 7 to its position of FIG. 8 represents an appreciable downward movement of this roll relative to the position of dancing roll 130 in FIG. 7, for instance about $\frac{3}{4}$ inch. Although the shift of guide roll 170 to the position of FIG. 8 would tend to shorten the indirect course of the strip from the line of action of the die to the spool, this is more than offset by the action of guide roll 171, and the movement of both guide rolls combined tends to enlarge the course. The roll 130 which is yieldingly biased is, of course, free to follow the downward movement of roll 171 so far as required to stabilize the tension and prevent any excess. However, the movement of roll 171 slightly away from roll 130 acts to insure that break-away of the strip is initiated under full tension.

I claim:

1. A label-applying machine for transferring labels from a label carrier strip to a receiving surface, comprising a rotary die having a segmental active surface, label carrier strip delivery means for delivering the label carrier strip to the die with successive labels in register with the die, a plurality of strip guides for the label carrier strip which has passed the die, a winding spool for the strip, the strip having an indirect course from the line of action of the die around said strip guides and to the spool, one of said guides adjacent to the die being movable bodily transversely of the course of the strip to allow the strip to move toward the die axis and by such movement withdraw away from the path of a surface receiving the label from the strip, means for so moving the last named guide in timed relation to the delivery of successive labels of the strip to the die, another of said guides being movable in synchronism with the last named guide through a path so related to the course of the strip that such movement of both guides combined tends materially to enlarge said course of the strip, and a yieldingly loaded guide movable by the strip in said course.

2. A label-applying machine for transferring labels from a label carrier strip to a receiving surface, comprising a rotary die having a segmental active surface, label carrier strip delivery means for delivering the label carrier strip to the die with successive labels in register with the die, a plurality of strip guides for the label carrier strip

which has passed the die, a winding spool for the strip, the strip having an indirect course from the line of action of the die around said strip guides and to the spool, one of said guides adjacent to the die being positioned to hold the strip away from the die axis and being movable bodily transversely of the course of the strip to allow the strip to move toward the die axis and by such movement withdraw away from the path of a surface receiving the label from the strip, means for so moving the last named guide in timed relation to the delivery of successive labels of the strip to the die, another of said guides being movable in synchronism with the last named guide through a path so related to the course of the strip that such movement of both guides combined tends materially to enlarge said course of the strip, and a yieldingly loaded guide movable by the strip in said course.

3. A label-applying machine for transferring labels from a label carrier strip to a receiving surface, comprising a rotary die having a segmental active surface, label carrier strip delivery means for delivering the label carrier strip to the die with successive labels in register with the die, a plurality of strip guides for the label carrier strip which has passed the die, a winding spool for the strip, the strip having an indirect course from the line of action of the die around said strip guides and to the spool, one of said guides adjacent to the die being movable bodily transversely of the course of the strip to allow the strip to move toward the die axis and by such movement withdraw away from the path of a surface receiving the label from the strip, means for so moving the last named guide in timed relation to the delivery of successive labels of the strip to the die, another of said guides being movable in synchronism with the last named guide through a path so related to the course of the strip that such movement of both guides combined tends materially to enlarge said course of the strip, and a yieldingly loaded guide movable by the strip in said course.

4. A label-applying machine for transferring labels from a label carrier strip to a receiving surface, comprising a rotary die having a segmental active surface, label carrier strip delivery means for delivering the label carrier strip to the die with successive labels in register with the die, a winding spool for the label carrier strip which has passed the die, the strip having an indirect course from the line of action of the die to the winding spool, means for intermittently operating the die and strip delivering means, strip guiding means movable bodily transversely of the course of the strip in timed relation to the operation of the strip delivering means to modify said course in a manner tending materially to enlarge said course and simultaneously cause a part of the strip adjacent to the die to withdraw away from the path of a surface receiving the label, and a yieldingly loaded means movable in a direction to enlarge said course for tensioning the strip between the die and winding spool.

5. A label-applying machine for transferring labels from a label carrier strip to a receiving surface, comprising a rotary die having a segmental active surface, label carrier strip delivery means for delivering the label carrier strip to the die with successive labels in register with the die, a winding spool for the label carrier strip which has passed the die, the strip having an indirect course from the line of action of the die to the winding spool, means for intermittently operating the die and strip delivering means, strip guiding means engaging the strip in said course and including two guides, and means for moving said guides simultaneously through different distances, such movement of each guide being a bodily movement transversely of the course of the strip, the one of said guides nearer to the line of action of the die being movable through the lesser distance and permitting the strip to move toward the die axis and withdraw away from the path of a surface receiving the label.

6. A label-applying machine for transferring labels

from a label carrier strip to a receiving surface, comprising a rotary die having a segmental active surface, label carrier strip delivery means for delivering the label carrier strip to the die with successive labels in register with the die, a winding spool for the label carrier strip which has passed the die, the strip having an indirect course from the line of action of the die to the winding spool, means for intermittently operating the die and strip delivering means, and strip guiding means engaging the strip in said course and including two guides movable together about a common axis, such movement of each guide being a bodily movement transversely of the course of the strip, the one of said guides nearer to the line of action of the die also being nearer to said common axis, such movement of the guides in one direction about said common axis permitting the strip to move toward the die axis and withdraw away from the path of a surface receiving the label.

7. A label-applying machine for transferring labels from a label carrier strip to a receiving surface, comprising a rotary die having a segmental active surface, label carrier strip delivery means for delivering the label carrier strip to the die with successive labels in register with the die, a winding spool for the label carrier strip which has passed the die, the strip having an indirect course from the line of action of the die to the winding spool, means tending to drive the strip delivering means, means for restraining the strip delivering means, strip guiding means movable bodily transversely of the course of the strip to modify said course in a manner tending materially to enlarge said course, and means including a cam rotatable with the die for releasing said restraining means and moving said strip guiding means.

8. A label-applying machine comprising a rotary die having a segmental surface for transferring labels from a label-carrier strip to a receiving surface, label-carrier strip delivery means for delivering the label-carrier strip to the die with successive labels in register with the die, the machine including guiding elements engaging the label-carrier strip which has passed the die, and means for tensioning said strip, the one of said guiding elements which is the first to engage the strip after passage of the strip past the line of action of said die being bodily shiftable in different directions which respectively permit the strip to approach nearer to the die axis and cause the strip to move farther away from the die axis, and means for so shifting the aforesaid first guiding element in such timed relation to the rotation of the die as to present the strip nearer to the die axis during transfer action of said segmental surface of the die than during idle rotation of said segmental surface.

9. A label-applying machine as claimed in claim 8 in which the first guiding element through its shifting tends to affect the length of strip path and a further one of said strip guiding elements is simultaneously bodily shiftable in directions in which it tends to affect the length of the strip path oppositely to the tendency of the first guiding element.
